YARN TENSIONING DEVICE FOR LOOM SHUTTLES

Joseph E. Blanchard, Millbury, Mass., assignor to Watson-Williams Manufacturing Company, Millbury, Mass., a corporation of Massachusetts

Application July 13, 1950, Serial No. 173,570

1 Claim. (Cl. 139—217)

1 The present invention relates to a yarn tensioning device for loom shuttles, and has for its object to provide improved means for adjusting and constantly maintaining the frictional force exerted on a yarn as it is drawn from a bobbin through the shuttle eye.

The yarn tensioning device of the present invention is particularly adapted for the use in connection with a yarn guide of the type that is mounted at the yarn delivery end of a shuttle chamber, with the yarn guide being in the form of a block which provides a yarn delivery channel. In passing through this channel, the yarn is subjected to a frictional force exerted by parallel plates between which the yarn moves, and the present invention provides improved means for adjusting and constantly maintaining the pressure exerted by these plates, so as to set up the desired amount of tension in the yarn as it is drawn through the guide, and the associated shuttle eye.

The above and other advantageous features of the present invention will hereinafter more fully appear from the following description, considered in connection with the accompanying drawings, in which,

Fig. 1 is a plan view of a loom shuttle provided with an adjustable yarn tensioning device embodying the present invention.

Fig. 2 is a view in side elevation of the yarn guide, shown in Fig. 1, removed from the shuttle and shown on an enlarged scale.

Fig. 3 is a bottom plan view of the yarn guide shown in Fig. 2.

Fig. 4 is a transverse sectional view along the line 4—4 of Fig. 2, looking in the direction of the arrows.

Fig. 5 is a fragmentary view showing the adjusting screw of the yarn tensioning device removed from the yarn guide, and on a still larger scale.

Fig. 6 is an end view of the screw shown in Fig. 5.

Figs. 7 and 8 are perspective views showing the adjusting screw and the opening in the yarn guide with which it cooperates.

Referring first to Fig. 1, the invention is shown for purposes of illustration as being embodied in a loom shuttle S, the body 1 of which provides a chamber 2, extending longitudinally of the shuttle for the reception of a bobbin 3. The butt of the bobbin 3 is held at one end of the chamber 2 by a suitable gripping device 4, and the tip of the bobbin extends to a point adjacent the opposite end of the shuttle chamber 2, so

2 that the yarn Y may be unwound from the bobbin and drawn through a yarn tensioning device before leaving the shuttle eye E.

The adjustable yarn tensioning device of the present invention is embodied in a yarn guide 5 which is generally in the form of a block 6 having parallel sides that are received between the walls of a slot 7 formed in the shuttle body 1, adjacent to the tip of the bobbin 3. The yarn guide 5 is shown in Figs. 2, 3 and 4 as having been removed from the shuttle S, with the guide being drawn on an enlarged scale, as compared to its actual size, in order to better show the construction of the parts entering into the adjustable tensioning device of the present invention.

As best shown in Figs. 1 and 4, the guide block 6 provides a yarn delivery channel 8 in line with the axis of the bobbin 3, for the passage of the yarn Y, and this channel 8 leads into a recess 9 formed in the block 6 for receiving a pair of yarn tension plates 10. The lower ends of the plates 10 are mounted freely on a pin 11 extending transversely of the block 6 across the recess 9, and the upper ends of the plates 10 are freely received in openings 12 provided on opposite sides of the yarn delivery channel 8.

By reason of their relatively loose support within the recess 9 of the block 6, the plates 10 are adapted to receive the yarn Y between them, when the yarn is led from the bobbin 3 and passed downwardly through the channel 8. The object of the present invention is to provide adjustable means for exerting pressure on the plates 10 which tends to hold them together, in order that a frictional force will be applied to the yarn Y, as it is drawn through the shuttle eye E, to set up and maintain a desired degree of tension in the yarn, as the shuttle S moves back and forth during operation of the loom.

For this purpose, each plate 10 has associated therewith an adjusting screw 13, which as best shown in Fig. 4, is adapted to be received within a threaded opening 14 provided in the side wall of the recess 9 in the block 6. The inner end of the screw 13 provides a seat 15 for the reception of a spring 16, the outer end of which bears on a tension plate 10, and obviously the position of the screw 13, with respect to the threaded opening 14, will determine the amount of pressure exerted by the spring 16. It will be evident from a consideration of Fig. 4 that the two plates 10 are held in yielding engagement with each other by the oppositely disposed springs 16, so that the frictional force applied to the yarn Y, while being drawn between the plates 10, will be deter-

mined by the positions occupied by the adjusting screws 13, within the openings 14.

The outer end of each screw 13 provides a transverse slot 17 for the reception of a tool for turning the screw within its opening 14, and each screw 13 provides means, turnable bodily therewith, for locking the screw within its opening 14, following an adjustment of the pressure exerted by its spring 16. As best shown in Figs. 5, 6 and 7, the screw 13 provides a pair of slots 18 extending longitudinally thereof across the screw threads 19, and these slots 18 are adapted to receive a locking member 20 in the form of a length of wire passing through an opening 21 extending across the screw, and so bent as to provide arms 22 lying in the slots 18. It will be apparent from a consideration of Figs. 5 and 7 that the arms 22 of the locking member 20 normally project slightly beyond the ends of the slots 18, with these arms 20 being sufficiently resilient to be compressed within the slots 18.

As best shown in Fig. 8, the opening 14 formed in the wall of the recess 9 provides a number of angularly spaced slots 23 extending across the threads 24, with the slots 23 being of substantially the same depth as the slots 18 in the screw 13. Therefore, when the arms 22 of the locking member 20 are initially compressed to lie within the slots 18, prior to the insertion of the screw into the opening 14, the arms 22 will spring outwardly into a pair of slots 23 whenever turning of the screw brings the slots 18 into register with the slots 23. With the arms 22 seated in a pair of slots 23, it is obvious that the screw 13 will be held against turning freely within the opening 14, so that the screw will tend to remain in a position wherein the slots 18 and 23 are in register.

Should it be desired to turn the screw 13 in either direction from its locked position, the application of a tool to the end slot 17 results in the application of a turning force that is sufficient to compress the arms 22 within the screw slots 18, thereby permitting the screw to turn. The compression of the arms 22 within the slots 18 and their simultaneous withdrawal from the slots 23, is facilitated by the fact that the arms 22 lie only partially within the slots 18, so that the threads 24 of the opening 14 exert a wedging action on the arms 22 adjacent to the opening 21, with the result that the arms 22 will be withdrawn from the slots 23, almost as soon as a positive turning force is applied to the screw 13.

The fact that each screw 13 is locked by the arms 22, at each partial turn thereof, insures that the pressure exerted on the plates 10 by the screws 13 can be adjusted very closely, so that the plates will exert just the desired amount of frictional drag on the yarn Y. In this way, the tension on the yarn required to draw it through the yarn guide, can be varied within narrow limits, with the assurance that when such an adjustment has been made, the screws 13 will remain in a given setting, and will not work loose and change the yarn tension during the opera-

tion of the shuttle in the loom. This ability of my improved device to maintain and constantly hold a given setting, is of great importance, in view of the fact that an ordinary adjusting screw would tend to turn out of its opening in the guide block, as a result of the repeated shocks to which any shuttle is subjected in being driven back and forth across a loom.

From the foregoing, it is apparent that by the present invention, there is provided an improved yarn tensioning device for loom shuttles, characterized by the provision of a tension adjusting screw that will hold its setting after an adjustment, to constantly maintain the desired amount of yarn tension.

I claim:

In a yarn tension adjusting device for loom shuttles comprising a yarn guide in the form of a block mounted at one end of the shuttle chamber and providing a yarn delivery channel, said block having a threaded opening in the side wall thereof with slots extending across the threads of said opening, a yarn tension plate freely supported within said block in line with said channel, an adjusting screw turnable within the side wall opening of said block, with a slot extending across the threads of said screw, and a spring interposed between the inner end of said screw and said tension plate, the improvement which consists in the provision of a locking member carried by and turnable with said screw, said locking member comprising a fixed portion extending transversely of the screw and a yieldable portion partially received in said screw slot, said yieldable portion having a free extremity receivable in one of the slots in the side wall opening of the block when said screw is turned to bring the slots on the screw and wall opening into register with each other, to maintain a given adjustment of said yarn tension plate, with turning of said screw in either direction of rotation from its locked position serving to withdraw said free extremity of the locking member from the engaged slot of the wall opening.

JOSEPH E. BLANCHARD.
